UNITED STATES PATENT OFFICE.

MILTON F. WILLIAMS, OF ST. LOUIS, MISSOURI, ASSIGNOR TO WILLIAMS PATENT CRUSHER AND PULVERIZER COMPANY, OF ST. LOUIS, MISSOURI, A CORPORATION OF MISSOURI.

CAGE CONSTRUCTION FOR MILLS.

1,340,643.

Specification of Letters Patent. Patented May 18, 1920.

Application filed July 14, 1917. Serial No. 180,548.

To all whom it may concern:

Be it known that I, MILTON F. WILLIAMS, a citizen of the United States, residing at the city of St. Louis, State of Missouri, have 5 invented a certain new and useful Improvement in Cage Constructions for Mills, of which the following is a full, clear, and exact description, such as will enable others skilled in the art to which it appertains to 10 make and use the same, reference being had to the accompanying drawings, forming part of this specification.

This invention relates generally to mills, and specifically to certain improvements in 15 means for mounting the screen or cage in such devices.

In the accompanying illustrations, I have shown the invention as applied to a rotary mill of the type wherein beaters or hammers 20 are operated within a cage or grinding cylinder, a portion of which comprises a foraminous screen through which the reduced material is discharged when of proper fineness. It is obvious, however, that the particular form of cage mounting which is 25 hereinafter claimed, may be utilized in other forms of machines besides those of this particular type.

The purpose of the invention is to provide 30 a form of screen mounting which will permit the ready and rapid removal and replacement of the screen so as to facilitate repair, adaptation of the machine to different materials, and variation in the predetermined grade or fineness of the products 35 which it will turn out.

A further object is to simplify the cage mounting so as to render the mill construction more economical, and provide a form 40 of mounting which is adapted to clamp the screen very firmly in place, and yet is adjustable to accommodate screens of a variety of thicknesses.

Other objects will be obvious or pointed 45 out hereinafter, reference being had to the accompanying drawing, in which—

Figure 1 represents a longitudinal sectional elevation of a rotary mill equipped 50 with my improved screen mounting;

Fig. 2 represents a detail in the nature 55 of a section through a portion of the screen and the parts forming the mounting therefor.

Referring to these illustrations by the 55 reference characters applied, let it be under-

stood that the numeral 1 designates generally a side frame portion of the machine, two of which said side frame portions are disposed counter-facing to form supporting and housing members for the operating 60 parts. The numeral 2 designates a cover portion which is removably mounted on the side frames 1 so that it may be moved away therefrom to expose inclosed parts. Numeral 4 designates a shaft arranged to be 65 suitably driven, and upon which are carried the beaters 5. A breaker plate 6 may be mounted on the frame portions with its work surface disposed in operative association with the beaters 5. A screen or cage 7 70 is supported on the frame portions for co-operation with the beaters 5, and together with the breaker plate 6 and cover portion 2, forms the arcuate wall of the grinding cylinder. The screen 7 may be foraminous 75 to permit the passage therethrough of sufficiently reduced material. As is well known in the art, different sorts of material require different kinds of cages or screens, and different mesh of screens are used on different occasions, depending upon the fineness of product desired. Therefore, it is quite desirable that the machine be such as to facilitate the removal and replacement of 80 screens.

In the production of my improved cage mounting, the side frame members 1 are provided with arcuate slots or grooves which lie on the arc which the screen is intended to occupy. As best seen in Fig. 2, these 90 slots, designated by the numeral 8, are formed with the side 8^a extending parallel to the axis of the grinding cylinder, and the opposite side 8^b extending angularly relative thereto and convergently toward the side 8^a. 95 These slots or grooves are open at the upper extremities of the frame portions 1, so that the screen 7 may be readily slipped into them. A plurality of arcuate wedge members 9, conforming to the grooves 8 in curvature and cross section, are adapted to be fitted into the grooves against the sloping side 8^b. These wedge members are adapted to be retained in place in the grooves by means of suitable fastening devices, such as 100 the bolts 10, which extend through the side frames 1 and may be drawn up by nuts 11 on the exterior of the mill. When the bolts are so drawn up, the wedge members 9 will be drawn into the grooves 8 and, by virtue 105 of

of their engagement with the inclined walls 8^b, will be wedged into engagement with the screen 7 so as to clamp it against the opposite walls 8^a. In the event the securing means pass through the wedge members 9, as illustrated in Fig. 2, the apertures in which they are seated will be properly elongated to permit the requisite transverse movement.

10 By virtue of the construction above described, the changing of screens in the mills is a very simple matter as it is necessary simply to back off the nuts 11 to an extent sufficient to release the screen from the 15 clamping pressure, and then to withdraw the screen, replace it with another, and then tighten up the bolts to clamp it in place. By virtue of this adjustable feature a wide variation in thickness of the screens used 20 may be accommodated, and all properly secured in place.

What I claim is:

The combination with a wall provided on its inner face with an arcuate groove, said 25 groove having an inclined face and a per-

forated plate having an edge thereof positioned in said groove opposite to the inclined face thereof, of an arc-shaped wedge member positioned in the groove between the perforated plate and the inclined face of 30 said groove, there being a slot formed in said wedge member, a clamping member passing through the wall adjacent to the groove and through the slot in the wedge member, the slot in said clamping member 35 being of such width as to permit the lateral movement of said clamping member, the inner end of the latter directly engaging the outer face of the arc-shaped wedge, and means adjustably mounted on the outer end 40 of said clamping member for drawing it through the wall and exerting pressure against the wedge member.

In testimony whereof I hereunto affix my signature this 9th day of July, 1917.

MILTON F. WILLIAMS.
